UNITED STATES PATENT OFFICE.

WILLIAM J. LINTON, OF JERSEY CITY, NEW JERSEY.

BOILER.

1,214,195.

Specification of Letters Patent. Patented Jan. 30, 1917.

Application filed October 19, 1912. Serial No. 726,619.

To all whom it may concern:

Be it known that I, WILLIAM J. LINTON, a subject of His Majesty the King of Great Britain, and a resident of Jersey City, in the county of Hudson and State of New Jersey, have invented certain new and useful Improvements in Boilers, of which the following is a specification.

This invention relates to boilers of the class known as water-tube boilers, and particularly to that type of water-tube boiler in which a series of three, or perhaps four, transverse drums or headers connected together by banks of water-tubes in a closed triangular, or quadrilateral, cycle are mounted within a suitable casing and the water, admitted to one of the drums or headers in the upper rear portion of the casing, is caused to circulate first downward, thence forward, and then upward and backward from one drum or header to another in succession by the flames and hot products of combustion which are conducted through the casing against the drums or headers and between and along the connecting banks of water-tubes in the opposite direction. In boilers of this type as heretofore constructed, the steam is disengaged in and run off from the upper part of the single upper drum, or one of two upper drums, which is connected up in and forms a part of the water-circulating system. The rapid circulation of the water, however, causes an ebullition of the water in the lower part of the steam-disengaging drum and, as a result, the steam produced is saturated with moisture.

The object of my present invention is to obviate this defect, and otherwise to increase the efficiency of boilers of the type in question.

With this end in view, the invention consists, broadly stated, in the provision of an additional drum, located within the casing and forming a part of the boiler but not of the water-circulating system, in which water is maintained by gravity on a level with the water in the rest of the boiler and to which the steam passes from the steam-disengaging drum and is superheated and dried during its passage from one to the other of these drums.

It also comprises the novel features of construction, arrangement, and combination of parts hereinafter described and particularly pointed out in the claims.

In the accompanying drawings, forming part of this specification, Figure 1 illustrates, in front elevation with parts broken away, and Fig. 2, in vertical longitudinal section on the line 2-2 of Fig. 1, a boiler containing one specific embodiment of my improvements.

Referring to the drawings, 1 is the usual boiler casing, of any suitable construction. The front wall 2 of the casing is provided with the customary fire and ash doors and additional doors conveniently located to give access to the interior of the boiler. The grate 3 is mounted in the usual manner between the front casing wall and rear bridge-wall or abutment 4. Suitably mounted within the boiler casing are the three usual drums, a steam-disengaging drum 5 in the upper rear portion of the casing, a mud drum 6 located directly below the steam-disengaging drum in the rear lower portion of the casing, and a water drum 7 at the front of the boiler on a level intermediate that of the two rear drums, which three drums are connected together in a closed triangular cycle by three banks of water-tubes, the vertical tubes 8, forwardly and upwardly inclined tubes 9, and rearwardly and upwardly inclined tubes 10. The flames and hot products of combustion are conducted from the fire-pot over the grate through the boiler to the outlet flue 11, as indicated by arrows, by means of the fire-arch 12, bridge-wall 4, baffles 13, 14, 15, 16, 17 and 18, and projecting ledge 19, while the water, admitted to the steam-disengaging drum 5 through the usual feed-water inlet 20, is thereby caused to circulate in the opposite direction, that is to say, from the steam-disengaging drum 5 to and through the mud drum 6 and thence to and through the water drum 7 and back to the steam-disengaging drum, all in the old and well-known manner.

The additional drum 21, which in effect constitutes a steam-dome or reservoir and is provided with steam-outlets 22, is located in the front of the casing on substantially the same level as or slightly above the steam-disengaging drum 5 with its lower side some three or four inches below the center line of the latter. These two drums are connected at their upper sides, above the baffle-plate 15 and the water level of the boiler, by the steam-tubes or pipes 23. Their lower sides are also connected by a water-pipe 24, lo-

cated at the side of the boiler, which through the upright arm 25 opens into the end of the steam-dome or reservoir some three inches above its lower side and extends forward to the front of the boiler where it makes connection with the water-gage 26 the upper end of which is in turn connected back with the upper side of the steam-dome by the pipe 27. The baffle-plate 15 is provided with front and rear transverse openings 28 and 29 which are respectively controlled by the two oppositely mounted and nearly balanced dampers 30 and 31.

The operation of the boiler will readily be understood from the above description. Flames and hot gases and other products of combustion are carried against the drums successively and between and along the connecting water-tubes in one direction while the water is caused to circulate through the closed water-circulating system in the opposite direction, in the usual manner as already stated. Instead, however, of being withdrawn from the steam-disengaging drum forming part of the water-circulating system, as heretofore, the steam disengaged therein passes over through the steam-tubes to the steam-dome or reservoir, is superheated by the hot gases on its passage thereto, and is withdrawn therefrom through the steam-outlets. The water-pipe, which connects the steam dome or reservoir with the steam-disengaging drum well below the normal level of the water in the boiler and out of the path of the steam as it passes upwardly to the steam-disengaging surface within this drum (or, as the equivalent thereof, a water-pipe connecting the steam-dome or reservoir with the mud-drum below the level of the circulating water and steam therein), maintains within the steam-dome or reservoir solely by gravity a supply of water which is quiescent because no steam circulates therethrough; and, as the opening in the water-pipe is about three inches above the lower side of the steam-dome, a certain amount of water will be retained therein even should the level of the rest of the water fall below its bottom, thus obviating any possibility of damage to this steam-dome from the hot gases which come in contact therewith, while, in the event of the boiler standing idle and condensation taking place therein, the surplus water will run back into the water-circulating system of the boiler. When the boiler is first started and before the steam generated in the steam-disengaging drum moistens the steam-pipes leading therefrom to the steam-dome, the dampers controlling the openings in the baffle-plate 15, are closed to protect these steam-pipes from injury, but as soon as the boiler gets fairly into operation these dampers are or may be opened so as to permit a part of the hot gases circulating through the boiler to

pass above the baffle-plate and so superheat and dry the steam as it passes through the steam-tubes from the steam-disengaging drum to the steam-dome. The steam thus collected in and withdrawn from the steam-dome is comparatively dry and is superheated, thereby increasing the efficiency and consequently the efficiency of the boiler.

While I have described the principle of my invention and what I now consider the best mode in which to apply that principle, it will of course be understood that the specific embodiment of the invention shown and described can be modified in its various details, within the scope of the appended claims, without departing from the spirit or sacrificing the advantages thereof. It is also to be understood that the term "drum", as used herein, defines and includes any form of header used to connect the banks of tubes and, specifically, a box header which is the equivalent of the drum.

What I claim as new, and desire to secure by Letters Patent, is—

1. A water-tube boiler comprising in addition to the usual drums and connecting water-tubes forming a closed water-circulating system, a steam-dome which is located partly below and partly above the normal level of the water in the water-circulating system, steam-superheating tubes which connect the steam-dome with the water-circulating system above the normal level of the water therein, and a water-pipe which connects the steam-dome somewhat above its lower side with the water-circulating system below the normal level of the water and outside the path of the steam therein.

2. A water-tube boiler comprising, in addition to the usual rear steam-disengaging and mud-drums, a front water-drum and connecting water-tubes, forming a closed water-circulating system, a steam-dome which is located in the front of the boiler casing with its lower side slightly below the normal level of the water in the boiler and is connected with the steam-disengaging drum above the water level of the boiler by steam-superheating tubes, and a water-pipe which connects the said steam-dome at a point between its lower side and the normal water level of the boiler with the lower side of one of the said rear drums.

3. A water-tube boiler comprising, in addition to the usual drums and connecting water-tubes forming a closed water-circulating system, an additional drum which is located in the boiler casing partly below and partly above the normal level of the water in the water-circulating system, steam-superheating tubes which connect said additional drum with the water-circulating system above the normal level of the water therein, a water-pipe which connects said additional drum with the rear part of the

water-circulating system outside the path of the steam therein, means for employing the hot gases which pass through the boiler to heat said additional drum and its connecting steam-superheating tubes, means for maintaining a supply of water in said additional drum, and means for protecting the steam-superheating tube connections from injury by the heat when the boiler is first started.

4. A water-tube boiler comprising, in addition to the usual drums and connecting water-tubes forming a closed water-circulating system, a drum which is located partly below and partly above the normal level of the water in the boiler and is connected with the boiler above the water level by steam-superheating tubes and below the water level solely by a connection therewith at a point outside the path of the steam therein.

5. A water-tube boiler comprising, in addition to the usual rear steam-disengaging and mud drums, front water-drum, and connecting water-tubes, forming a closed water-circulating system, a drum which is located in the front of the boiler casing with its lower side slightly below the normal level of the water in the boiler and is connected above the water level of the boiler with the rear steam-disengaging drum by steam-superheating tubes and below the water level of the boiler solely by a water connection with the lower side of one of the said rear drums.

6. A water-tube boiler comprising, in addition to the usual rear steam-disengaging and mud drums, front water-drum, and connecting water-tubes, forming a closed water-circulating system, a drum which is located partly below and partly above the normal level of the water in the boiler and has no direct connection with the front water-drum, steam-superheating tubes which connect the said additional drum with the boiler above the normal water level therein, and a water-pipe which connects the said additional drum at a point between its lower side and the normal water level of the boiler with the lower side of one of the said rear drums.

7. A water-tube boiler comprising, in addition to the usual drums and connecting water-tubes forming a closed water-circulating system, a steam-dome, means for maintaining within the lower part of the steam-dome a quiescent body of water supplied thereto through a connection with the boiler at some point outside the path of the steam therein, means for transferring the

steam generated within the boiler to the upper part of the steam-dome, means for superheating the steam during its transfer to and while within the steam-dome, and means for drawing off the superheated steam from the steam-dome as fast as it is collected therein.

8. A water-tube boiler comprising, in addition to the usual rear steam-disengaging and mud drums, front water-drum, and connecting water-tubes, forming a closed water-circulating system, a drum which is located in the front of the boiler casing partly below and partly above the normal level of the water in the boiler and has no direct connection with the front water-drum, a water-pipe which connects the said additional drum at a point between its lower side and the normal water level of the boiler with the lower side of one of the said rear drums of the boiler at a point outside the path of the steam therein, means for transferring steam from the upper part of the said rear steam-disengaging drum to the upper part of the said additional drum, means for superheating the steam during its transfer to and while in the said additional drum, and means for withdrawing the superheated steam from the said additional drum as fast as it collects therein.

9. A water-tube boiler comprising, in addition to the usual rear steam-disengaging and mud drums, front water-drum, and connecting water-tubes, forming a closed water-circulating system, an undivided drum which is located in the front of the boiler casing slightly below and largely above the normal level of the water in the boiler and has no direct connection with the said front water-drum, means for maintaining within the lower part of the said additional drum a quiescent body of water supplied from the lower part of one of the said rear drums outside the path of the steam therein, means for transferring steam from the upper part of the said rear steam-disengaging drum to the upper part of the said additional drum, means for utilizing the hot gases which pass through the boiler to heat the steam while it is being transferred from the said rear steam-disengaging drum to the said additional drum, and means for withdrawing from the said additional drum the steam as it collects therein.
